UNITED STATES PATENT OFFICE.

ARTHUR WONDERLICH AND HENRY A. CROZIER, OF GENOA, NEBRASKA.

STRAW AND MANURE SPREADER.

1,209,532.

Specification of Letters Patent.

Patented Dec. 19, 1916.

Application filed May 31, 1916. Serial No. 100,941.

To all whom it may concern:

Be it known that we, ARTHUR WONDERLICH and HENRY A. CROZIER, citizens of the United States, residing at Genoa, in the county of Nance and State of Nebraska, have invented new and useful Improvements in Straw and Manure Spreaders, of which the following is a specification.

This invention relates to machines for spreading straw, manure and the like of that class in which a wheeled vehicle carrying the load is equipped with mechanism for moving the load rearwardly on the vehicle and with mechanism for spreading or scattering the load.

The invention has for its object to produce a machine of the class described in which simple and improved means are provided for supporting the load and for moving it rearwardly with respect to the platform on which it is supported.

A further object of the invention is to simplify and improve the construction and operation of the carrying mechanism as well as of the spreading mechanism.

A further object of the invention is to produce simple and improved means for automatically stopping the carrying mechanism when the load has been discharged.

With these and other ends in view which will readily appear as the nature of the invention is better understood, the same consists in the improved construction and novel arrangement and combination of parts which will be hereinafter fully described and particularly pointed out in the claims.

In the accompanying drawings has been illustrated a simple and preferred form of the invention, it being, however, understood that no limitation is necessarily made to the precise structural details therein exhibited, but that changes, alterations and modifications within the scope of the claims may be resorted to when desired.

In the drawings, Figure 1 is a top plan view of a machine constructed in accordance with the invention. Fig. 2 is a side elevation, partly in section. Fig. 3 is a rear elevation. Fig. 4 is a detail view of the spreading device. Fig. 5 is a perspective detail view of the follower which is adjustably connected with the conveyor chains. Fig. 6 is a transverse sectional view taken on the line 6—6 of Fig. 2.

Corresponding parts in the several figures are denoted by like characters of reference.

The invention has been shown as being applied to an ordinary wagon bed or rack supported on front and hind wheels 16, 17. The hind wheels 17 are provided with spur wheels 18 from which motion is transmitted by chains 19 to spur wheels 20 carried by a shaft 21 which is supported adjacent to the rear end of the rack. A counter shaft 22 is supported slightly below and to the rearward of the shaft 21.

Slidably mounted on a non-circular portion of the shaft 21 for rotation with said shaft is a sleeve or hub 23 carrying spur-wheels 24, 25 of different diameters at the ends thereof. Fixed on the shaft 22 for rotation therewith is a sleeve or hub 26 having spur wheels 27, 28 of different diameters mounted thereon intermediate the ends thereof, the parts being so proportioned and arranged that by sliding the hub 23 along the shaft 21 the spur wheel 24 may be placed in mesh with the spur wheel 27, or the spur wheel 25 may be placed in mesh with the spur wheel 28, or the hub 23 may be placed in a neutral position where the spur wheels 27, 28 will be positioned intermediate the spur wheels 24, 25 and out of mesh with either. It will be seen that by this mechanism motion at various rates of speed may be transmitted from the shaft 21 to the shaft 22, or the motion of the shaft 22 may be interrupted. A spring 29 forces the sleeve or hub 23 in the direction of a cam 30 which is provided with several shoulders or offsets, and by the longitudinal movement of which the sleeve 23 may be moved against the tension of the spring 29 for the purpose of adjusting it to any required position. The cam member 30 is connected by an operating rod 31 with a hand lever 32 at the front end of the rack, by means of which the cam may be adjusted for the purpose of starting and interrupting the motion of the shaft 22 and for varying the speed thereof. The lever 32 is provided with a stop member 33 adapted to engage any one of several notches 34 in a segment rack 35, whereby the lever and the parts controlled thereby may be securely retained at any desired adjustment.

The shaft 22 carries a sprocket wheel 36 which is connected by a chain 37 with a sprocket wheel 38 which is loosely mounted on the shaft 21 for rotation on said shaft. The hub of the sprocket wheel 38 has a clutch member 39 which is engaged by a clutch member 40 on the hub of a sprocket

wheel 41 which is slidably and revolvably mounted on the shaft 21, said sprocket wheel being pressed in the direction of the sprocket wheel 38 by a spring 42, whereby the said 5 sprocket wheels 38 and 41 will be caused normally to rotate in unison.

A carrying platform is provided, the same being supported on the wagon bed or rack, said wagon having been shown as being 10 composed of two separate parts or members B, each member consisting of a wooden frame 43 on which a floor 44 of sheet metal is supported. By making the platform of two separate parts or members it may be 15 readily fitted to wagon beds or racks of different dimensions, and it may also be more conveniently handled and stored when not in use than would be the case if it were made to consist of a single member. The frames 20 43 are provided with cross bars 45 at suitable intervals whereby the sheet metal floor will be supported against sagging. Shafts 46, 47 are supported for rotation at the front and rear ends of the platform, said shafts being 25 equipped with sprocket wheels 48 over which the conveyer chains 49 are trained, the lower leads of said conveyer chains passing beneath the platform, as shown. The platform frames are also provided at the sides thereof 30 with upwardly extending flanges 50 constituting guards whereby the chains will be retained in position. The shaft 46 at the forward end of the platform has a sprocket wheel 51 which is connected by a chain 52 35 with the sprocket wheel 41 on the shaft 21 from which motion may thus be transmitted to the conveyer chains. The conveyer chains 49 may be connected together at suitable intervals by slats or cross bars 53.

46 A follower or end gate is provided, the same comprising a base frame 54, an upright frame 55 rising at the forward end of the base frame, and brace members 56 that connect the upper end of the upright frame with 45 the rearward end of the base frame. The base frame is provided with hooks 57 adapted to engage the links of the conveyer chains 49 with which the follower may thus be connected for the purpose of pushing or sliding 50 the load along the platform and also preventing the said load from toppling forward. The upright frame 55 of the follower is provided with load engaging slats 58 which may be arranged diagonally and otherwise as shown.

The spreader is composed of a downwardly and rearwardly inclined frame 59 which is supported adjacent to the rearward end of the rack, said rack being equipped 60 with side members 60 to retain the load in position. The frame 59 is provided at its upper and lower ends with shafts 61, 62 having sprocket wheels 63 over which is trained an endless conveyer composed of chains 64 65 and cross slats 65, the latter being equipped

with spikes 66. The lower shaft 62 is provided at the ends thereof with pinions 67 meshing with spur wheels 68 which are mounted for rotation on stub shafts 69, said hubs being also equipped with sprocket 70 wheels 70 which are connected by chains 71 with sprocket wheels 72 fixed on the shaft 22.

A hood or chute 73 is provided through which the material detached from the load by the spreader is discharged, the motion of 75 the spreader being sufficiently rapid to scatter the material over the ground, and the hood serving as a wind guard to prevent the loose material from being blown away. In like manner the hood serves to prevent the 80 material from being blown into the gearing and interfering with the movement thereof.

Supported for rotation adjacent to the rearward end of the platform is a rock shaft 74 having an upwardly extending arm 75 85 that lies in the path of a tappet member 76 which projects laterally from the follower that is connected with the conveyer chains. The shaft 74 also has an arm 76 which is connected by a link 77 with one arm of a bell 92 crank 78, the other arm of which has a terminal fork 79 that engages the hub of the sprocket wheel 41, enabling said hub to be retracted against the tension of the spring 42, thereby disconnecting the clutch members 93 95 and 40 and interrupting the transmission of motion from the shaft 21 to the shaft 46 whereby the endless conveyers are operated.

In the operation of this invention, the 100 load is placed on the platform at the front end of which the follower has been previously mounted and connected with the conveyer chains. By actuating the lever 32 the sleeve 23 carrying the spur wheels 24, 25 is 105 placed in a neutral position with respect to the spur wheels 27, 28, thereby interrupting transmission of motion to the moving parts of the mechanism while the load is being hauled to the field where it is to be discharged. By manipulating the lever 32 the sleeve or hub 23 is now actuated to place one of the spur wheels carried thereby in mesh with one of the spur wheels 27 or 28, thereby 110 causing motion at the desired speed to be transmitted to the shaft 22 and from said shaft through the mechanism described to the conveyer chains and also to the spreader. As the wagon is being drawn over the field the load will be moved forwardly by the 115 conjoint action of the conveyer chains and the follower connected therewith, and the material of the load is spread or scattered on the ground. When the load has been discharged the tappet member 76 of the follower will engage the arm 75 of the rock shaft 74, partly rotating said shaft and causing the bell crank 78 to move the sprocket wheel 41 against the tension of the spring 42, disconnecting the clutch members 93 and 120 95

40 and interrupting the movement of the conveyer chains, this interruption taking place automatically and without supervision by the operator, thereby avoiding any possibility of accident or breakage of the parts. The improved spreading device is very simple in construction and effective in operation, and it may be readily applied to and used in connection with hay racks or wagons 10 of conventional type.

Having thus described the invention what is claimed as new, is:—

1. In a machine of the class described, a rack having front and rear supporting 15 wheels, a platform composed of two lateral members mounted on the rack, each member consisting of a rectangular wooden frame, sheet metal flooring secured thereon, and guard flanges at the sides of the frame, shafts supported for rotation at the front and rear ends of the platform, endless conveyer chains trained over the shafts, and means for operating the endless conveyer chains by power derived from the rear supporting 20 wheels.

2. In a machine of the class described, a rack having front and rear supporting wheels, a transverse main shaft supported for rotation adjacent to the rearward end of 25 the rack and receiving motion from the rear supporting wheels, a counter shaft, means for transmitting motion at various speeds from the main shaft to the counter shaft, a sprocket wheel revoluble on the main shaft and receiving motion from the counter shaft, a platform mounted on the rack and having shafts at its front and rear ends, endless conveyer chains trained over the platform shafts, and means including a clutch 30 device for transmitting motion from the sprocket wheel on the main shaft to the rearward platform shaft, in combination with a follower connected with the con-

veyer chains, and means including a tappet on the follower, and a rock shaft mounted 45 on the platform and having an arm extending in the path of the tappet member for actuating the clutch to interrupt the transmission of motion to the platform shafts.

3. In a machine of the class described, a rack having front and rear supporting wheels, a transverse main shaft supported adjacent to the rear end of the rack and receiving motion from the rear supporting 50 wheels, a counter shaft having sprocket 55 wheels at the ends thereof, means for transmitting motion at variable speed from the main shaft to the counter shaft and for interrupting such motion, a platform supported on the rack, endless conveyer chains 60 guided over the platform, means for driving said conveyer chains and for interrupting the motion thereof, a spreader frame supported in a downwardly and rearwardly inclined position at the rearward end of the 65 rack, shafts at the upper and lower ends of said spreader frame, endless chains trained over said shafts and carrying spiked slats, spur wheels mounted on the lower spreader shaft at the ends thereof, stub shafts 70 mounted on the spreader frame, hubs mounted on the stub shafts, each hub having a spur wheel meshing with a spur wheel on the lower spreader shaft and each hub having also a sprocket wheel, and chains trained 75 over the last mentioned sprocket wheels and over the sprocket wheels on the counter shaft.

In testimony whereof we affix our signatures.

ARTHUR WONDERLICH.
HENRY A. CROZIER.
